UNITED STATES PATENT OFFICE

170,929

CLOCK OR SIMILAR ARTICLE

Kaspar Lendrait, Chicago, Ill.

Application March 9, 1953, Serial No. 23,967

Term of patent 14 years

(Cl. D42—7)

To all whom it may concern:

Be it known that I, Kaspar Lendrait, a citizen of the United States, residing at Chicago, in the county of Cook, and State of Illinois, have invented a new, original, and ornamental Design for a Clock or Similar Article, of which the following is a specification, reference being had to the accompanying drawing, constituting a part hereof.

Fig. 1 is a front elevational view of a clock or similar article showing my new design;

Fig. 2 is a side elevational view thereof; and Fig. 3 is a top plan view of the same.

I claim:

The ornamental design for a clock or similar article, substantially as shown.

KASPAR LENDRAIT.
